UNITED STATES PATENT OFFICE

HARRY E. PLATT, OF OTTUMWA, IOWA

AUTOMATIC PRESSURE GAUGE

Application filed January 21, 1929. Serial No. 333,987.

My invention relates to improvements in automatic pressure gauges, and it consists in the combinations, constructions, and arrangements herein described and claimed.

5 An object of my invention is to provide an automatic pressure gauge which may be used for air, gas, steam, or liquids, but which is especially adapted for use in connection with pressure tanks for passing air under pressure into vehicle tires.

A further object of my invention is to provide a device of the type described which may be adjusted so as to allow a predetermined amount of air under pressure to enter the tire.

15 A further object of my invention is to provide a device of the type described in which the adjusting means is disposed where it can be readily actuated.

20 A further object of my invention is to provide a device of the type described which has novel means for indicating to the operator when the main valve is opened and when the main valve is closed.

25 Other objects and advantages will appear in the following specification, and the novel features of the invention will be particularly pointed out in the appended claims.

My invention is illustrated in the accompanying drawing forming part of this application, in which

Figure 1 is a vertical sectional view of my device, portions thereof being shown in elevation,

Figure 2 is a top plan view of a portion of my device,

Figure 3 is an enlarged detail view of a signalling means, and

Figure 4 is a sectional view taken along the line 4-4 of Figure 1.

40 In carrying out my invention I provide a body portion 1, having a main inlet passageway 2 and an outlet passageway 3 separated from each other by means of a partition 4 but arranged to communicate with each other through an opening 5 provided in the partition. A cylinder 6 is provided in the body portion 1, and is provided with an open end 7 which is arranged to receive a cover 8.

45 A valve piston 9 is movably disposed in the cylinder 6 and is provided with stop mem-

bers 10 which extend upwardly and are arranged to engage with the cover 8. A spring supporting piston 11 is movably disposed in the cylinder 6 and is provided with a center opening 12. A valve stem 13, which has a main valve 14 mounted upon one end, slidably extends through the opening 12 and has the other end rigidly secured to the valve piston 9. A compression spring 15 is disposed between the two pistons 9 and 11.

55 An actuating lever 16 has one end connected to the body portion by means of a connecting link 17. Supporting arms 18 are rigidly carried by the cover 8 and pivotally support actuating links 19. The actuating links 19 each have one of their ends pivotally connected to the lever 16 at 20, and their other ends operatively connected to draw rods 21. The draw rods 21 are slidably disposed in packing members 22 which are carried by the cover 8. The draw rods 21 slidably extend through the valve piston 9 and have their inner ends rigidly secured to the spring supporting piston 11.

60 A signalling means is provided and is composed of an outer tube 23 having a cut-away whistle portion 24 disposed therein. This tubular portion is carried by the cover 8 and is provided with an air inlet opening 25. An inner tubular member 26 is carried by the valve piston 9 and is movably disposed in the outer tubular member 23. An opening 27 is provided in the inner tubular member 26 and is arranged to align with the opening 25 when the tubular member 26 is moved with respect to the tubular member 23.

65 A spring pressed auxiliary valve 28 is disposed in the end of the body portion 1 for providing an outlet for the passageway 3 when opened. A by-pass 29 is disposed in the body portion 1 for providing communication between the passageway 3 and the upper portion of the cylinder 6.

70 An indicating arm 30 is pivotally secured to the body portion 1 at 31 and is provided with a plurality of teeth 32. The teeth 32 provide notches 33 adjacent to which are disposed indicating lines 34. The indicating arm 30 extends through an opening 35 in the lever 16. A tongue member 36 is carried by

the lever and is receivable in the notches 33. A spring pressed block 37 is disposed in the lever 16 for holding the indicating arm 30 in engagement with the tongue member 36.

8 From the foregoing description of the various parts of my device, the operation thereof may be readily understood. Let us assume that the body portion 1 is secured to an air hose 38 which is arranged to provide air 10 under pressure to the body portion. Let us further assume that the operator wishes to pass air under pressure into a tire until the pressure in the tire has reached forty pounds. The operator will first force the lever 16 15 downwardly by pressing upon the handle portion 39 until the tongue portion 36 is disposed in the notch 33 adjacent the indicating line numbered 40 upon the indicating arm 30. By pressing the lever 16 downwardly, the draw 20 rods 21 will be moved upwardly thus moving the spring supporting piston 11 upwardly in the cylinder 6. The tension of the spring 15 will also force the piston 9 upwardly carrying with it the valve 14. The movement of 25 the piston 9 in the upward direction is limited by means of the stop members 10 so that the piston 9 will at all times be positioned beneath the outlet of the by-pass 29. If the piston 11 is moved upwardly a greater distance 30 than the piston 9 is allowed to move, the spring 15 will be compressed to take care of this additional movement of the piston 11.

When the main valve 14 is moved away 35 from the opening 5, the air under pressure is allowed to pass from the inlet passageway 2, through the opening 5, and into the passageway 3. By connecting the end of the body portion adjacent the valve 28 with the valve stem of the vehicle tire, the valve 28 40 will be moved from its seat thus allowing the air under pressure to enter the tire. The air under pressure will continue to pass into the tire until the pressure in the tire has reached forty pounds. The pressure in the 45 outlet passageway 3, the by-pass 29, and the cylinder 6 will be the same as in the tire. The spring 15 is of such a tension that the main valve 14 will be held open until the predetermined amount of air has passed into the tire. This predetermined amount of air will 50 be sufficient pressure to force the piston 9 downwardly against the tension of the spring and close the valve 14.

During the movement of the valve 9 in the 55 upward direction the opening 27 of the signalling means will align with the opening 25 and then pass beyond the opening 25. When the opening 27 is in alignment with the opening 25 a portion of the air under pressure will pass through these openings and through the opening 24 creating a whistling sound. This sound will notify the operator that the main valve 14 has been opened. After 60 the desired amount of air has passed into the tire the piston 9 is forced downwardly 65

thus closing the main valve 14. The opening 27 will again align and pass the opening 25 and will in this manner notify the operator that the main valve 14 is closed and that a sufficient amount of air has passed into the 70 tire.

I claim:

1. A device of the type described comprising a body portion having an inlet passageway and an outlet passageway, said body portion having a partitioning portion disposed between said inlet and outlet passageways, said partitioning portion having an opening therethrough, a valve member normally disposed in said opening and seating on said partitioning portion, said body portion being provided with a cylinder, a cylinder head removably connected with the body portion, an upper and a lower piston member movably disposed in said cylinder in spaced-apart 75 relation, spring means disposed between said spaced-apart piston members, said upper piston member being provided with stop members for limiting the movement thereof, said body portion having a passageway for providing communication between the outlet passageway and said cylinder between the upper piston member and the cylinder head, said main valve being provided with a valve stem slidably extending through said lower piston member and fixedly connected with the upper piston member, a pair of actuating rods fixedly connected with said lower piston member and slidably extending through said upper piston member and the cylinder head, an actuating lever, link means operatively connecting said actuating lever with the body portion and the actuating rods, a notched indicating arm having one end movably connected with the body portion and extending through an opening in said actuating lever, said arm being provided with indicia opposite the notches, and means mounted on said lever for engaging the notches of said indicating arm. 80

2. A device of the type described comprising a body portion having an inlet passageway and an outlet passageway, said body portion having a partitioning portion disposed between said inlet and outlet passageways, said partitioning portion having an opening therethrough, a valve member normally disposed in said opening and seating on said partitioning portion, said body portion being provided with a cylinder, a cylinder head removably connected with the body portion, an upper and a lower piston member movably disposed in said cylinder in spaced-apart 100 relation, spring means disposed between said spaced-apart piston members, said upper piston member being provided with stop members for limiting the movement thereof, said body portion having a passageway for providing communication between the outlet passageway and said cylinder between the upper 105 piston member and the cylinder head, an actuating lever, link means operatively connecting said actuating lever with the body portion and the actuating rods, a notched indicating arm having one end movably connected with the body portion and extending through an opening in said actuating lever, said arm being provided with indicia opposite the notches, and means mounted on said lever for engaging the notches of said indicating arm. 110
